BALL GAME APPARATUS

Richard W. Conner, Waynesboro, Pa., assignor of two-fifths to Elva Negley Conner, Waynesboro, Pa.

Application July 9, 1952, Serial No. 297,847

2 Claims. (Cl. 273—119)

This invention relates primarily to improvements in a game board so constructed and arranged as to be adaptable for use in playing a multiplicity of games, primarily by means of a projector, the latter being shiftable to a number of positions in accordance with the requirements of the game to be played and the game board incorporating interchangeable parts providing facilities for receiving the discharged projectiles.

Generally the game board includes a flat panel having a frame for retaining the same in a horizontal plane and simultaneously providing rails or guardways about the game board.

Another feature of the development is the provision of elongated compartments at each end of the board formed between the board ends and the frame or rail, the compartments being divisible by means of removable, shiftable panels into a predetermined number of properly located sub-compartments of desired form and capacity to receive and retain the projectiles in accordance with the rules of the game being played.

Another feature of the game board is the provision of removable corner rail sections, preferably formed at the junction of the side rails and end rails, these corner rail sections providing continuity between the connected parts, and being interlocked with the side and end rails to prevent their displacement and normally comprehending the upper portion of the rails at the corners of the structure as determined by the plane of the game board, it being understood that the corner pieces are hereinafter to be referred to as corner gates, although the corner pieces may be included in the general term of removable guard rail sections, such as are provided in the end rails to facilitate the mounting of the projector intermediate the ends of the end rails.

Another object of the present invention is the provision of diagrams on the surface of the playing board, the diagrams including guide lines and markers permitting the adaptation of the board for use in a series of games involving the surface projection of a projectile from a suitable source such as is required in many simulated games, such as baseball and the like.

Another feature of the present development is the provision of a projector having a shiftable mounting permitting its placement at desired positions at the end of the board, the projector including a power cylinder with means for regulating the amount of impact with which the projectile is to be impelled and the further provision of a swivel mounting for the projector, and a magazine, the latter permitting the use of a multiplicity of projectiles which are automatically controlled and fed upon the operation of the impact plunger as will be more fully hereinafter set forth.

Another object of the invention is the utilization of a plurality of boxes shaped to be received in the end compartments and designed for retaining projectiles, hazards and targets and/or functioning as bankboards.

Other features of the invention reside in the provision

2

of a multiplicity of carefully designed playing pieces to be used by the players separately or in combination in the playing of different games, the playing pieces in some instances constituting hazards or defense elements, and in other instances forming auxiliary projectiles or buffer elements.

Further objects of the invention will more clearly hereinafter appear by reference to the accompanying drawings forming a part of this application, in which like characters of reference designate corresponding parts throughout the several views, in which:

Fig. 1 is a perspective view of the invention showing some of the parts exploded to illustrate their association within the assembly;

Fig. 2 is a longitudinal sectional view of the invention;

Fig. 3 is a fragmentary enlarged perspective showing one end of the board and illustrating certain of the targets assembled in playing position;

Fig. 4 is an additional fragmentary perspective showing a different arrangement of targets and projector;

Fig. 5 is a perspective view of the projector with the magazine in position for assembly;

Fig. 6 is a top plan view of the magazine;

Fig. 7 is an end view of the projector;

Fig. 8 is a top plan view of the projector;

Fig. 9 is a side elevation of the projector;

Fig. 10 is a vertical section through the chute from the magazine;

Fig. 11 is a similar view illustrating the trigger in elevation;

Fig. 12 is a vertical sectional view through a portion of the projector and the magazine with the projectiles arranged for operation of the projector;

Fig. 13 is a similar view showing the projectiles and trigger mechanism actuated by the impact plunger;

Fig. 14 is a similar and additional view showing the operation of the parts after impact from the plunger;

Fig. 15 is a perspective view of the stop member or power selector;

Fig. 16 shows a projectile;

Figs. 17 through 42 illustrate various forms of targets and hazards used in the playing of various games;

Figs. 43 through 50 illustrate various layouts of the targets and hazards used in the playing of various games.

Referring now to Figs. 1, 2, 3 and 4, there is illustrated the structure of the game board per se, this board including a flat smooth rectangular panel 1 supported by a frame including side frame elements 2 and end frame elements 3. The marginal edges of the panel 1 project into a groove as shown at 4 in the side frame members 2, this groove extending horizontally and medially throughout the longitudinal inner surface of the frame member 2 and spacing the panel medially of the height of the side framing members so that such side frame members 2 form longitudinal side supports as well as side guard rails. The transverse end supports 3 of the panel are positioned beneath the panel end for the greater portion of their thickness but have outer faces projecting beyond the ends of the panel as best shown in Fig. 2, and provided with a series of vertical grooves or slots 5 to facilitate the positioning of partitions as will be more fully hereinafter described.

A plurality of transverse supports or stays 6 are arranged throughout the length of the panel 1 and connect the side frame members 2, these supports 6 having a depth equal to the depth of the end frame members 3 to provide a uniform support throughout the length of the panel. The side frame members 2 project beyond the end frame members 3 and are connected with the end walls 7, the latter being of the same height as the side frame members 2 and being formed with vertical slots 8

arranged for association with the slots 5 in seating partitions 9. The ends of the side frame members 2 are reduced in height as at 19 as defined by shoulder 11 to approximately the plane of the top of panel 1, and the end walls 7 are similarly cut away to receive the corner blocks or gates 12, these corner blocks 12 having projecting areas 14 defined by shoulders 15 to form head projections which engage the adjacent vertical faces of the side frame members 2 and end walls 7 to lock the corner members 12 against lateral displacement and to reinforce the corner structures. The corner members 12 are further provided with inner angular faces 16, which faces extend downwardly to the base 17 of the end pockets or wells formed between the ends of the panel 1 and the end rail 7 throughout the end structures of the board. The corner pieces 12 seat upon the upper faces of the side rails 2 and end rail 7 indicated in Fig. 1 at 18, these upper faces lying in the same plane as the top face 19 formed medially in the end rail 7 for the reception of the gate pieces 20, the ends of which are notched at 21 to receive the triangular projections 22 in the rail ends as best shown in Fig. 1. The corner pieces 12 and the central gate 20 form with the side and end rails a continuous rail structure when these parts are in place.

The surfaces 19 which receive the center gates 20 are formed with openings or recesses 23 which receive swivel pins of the projector to be hereinafter described and indicated generally by reference character A. The swivel mounting of the projector A at the corners is in the openings 23^a, these openings being so positioned as to permit an arc of movement of the projector to fully cover the playing surface. The recesses or openings 23^a which receive the swivel pin 40 preferably extend through the panel 1 and into the end support or brace 3 as best shown in Fig. 1. The foregoing structure provides an elongated flat playing board with wells at each end capable of being divided into a plurality of smaller areas by partitions 9, with means for mounting a projector at three separate positions at each end of the board and with further means for closing the gate openings when these openings are not in use. The board itself is laid off with a plurality of diagrams capable of facilitating the playing of a multiplicity of games which are to be herein-after more fully described. The structure provides also for the mounting of the projector in substantially the plane of the playing board and for the movement of the projector from a position approximating the longitudinal center line of the board to alternate positions at the end corners of the board, as may be required by the rules of the game or by requirements in playing a game as determined by a player.

The pockets or wells at the ends of the playing board, in addition to being provided with means for partitioning, are also adapted to cooperate with removable receptacles B and B', these receptacles being of proper depth to lie with their top edges flush with the top edges of the guard rails 2 and 7 and to fill the wells from sidewall to sidewall and to be removable and interchangeable as required. Obviously the end receptacle B' is provided with a diagonal end face 25 which is adapted to abut about the diagonal faces 16 of the corner pieces 12. The use of the receptacles, two of which are shown in position in Fig. 4, will be apparent from a further description of the specific games and may be used as bank-boards or for containing playing parts or projectiles or any of the equipment utilized in the use of the apparatus.

The proposed structure may be made of metal, plywood, or any suitable composition, or may be made of a combination of these materials which might be found most desirable in production and in providing against breakage or warping of the parts. The transverse braces 6 may or may not be necessary, and their number may be varied in accordance with requirements of the material used in construction of the panel 1.

It will be noted that the receptacles B and B' when

used will have their inner faces positioned to form a bank-board for the projectiles, and their length and arrangement may be altered to provide for interchangeable use within the scope of the invention. Generally the same is true with reference to the grooves 5 and 8, these grooves being shown in banks or spaced series with one medially arranged. The actual and specific arrangement of these grooves will be a matter of choice and can be modified without departing from the spirit of the invention.

The projecting apparatus and the magazine therefor are best illustrated in Figs. 5 through 15 and are designed for handling projectiles of the marble type. The projector itself is in the form of an elongated chamber having sidewalls 30, bottom 31, top 32, and end wall 33. The end wall 33 is formed with a central opening 34 for the passage of the shaft 35 of the projector member, which latter includes the impact face or panel 36 and the handle or knob 37. To provide energy for operating the projector there is a spiral compression spring 38 arranged on the rod 35 between the inner face of the end wall 33 and the pusher plate 36. Between the knob or handle 37 and the outer face of the end wall 33 there is a cushioning spiral spring 39 on the rod 35, the latter softening the impact by compression at the end of the projecting stroke under the energy provided by the compression of spring 38. A vertical pin 40 extends downwardly from the bottom wall 31 of the structure for seating in any of the openings 23 or 23^a provided in the end portion of the game board structure.

The top structure 32 of the projector casing is longitudinally slotted at 41 medially of its width and the top surface thereof throughout the greater portion of its length is formed with indicating marks or a selector scale 35 at each of its longitudinal marginal edges as at 42 to permit the positioning of a stop member or power selector shown in Fig. 15. The stop member or power selector is formed preferably from an elongated piece of sheet metal and is provided with a longitudinally concave portion 45 for receiving the thumb of an operator and an arched and downwardly extending portion 46 having transverse spaced flat edge portions 47 adapted to travel along the top face of the top wall 32 of the projector and a transverse clamp extension plate 48 depending therefrom by a medial neck portion 49, the clamp plate 48 being spaced by the neck 49 from the spaced transverse edges 47 a distance slightly greater than the thickness of the material forming the top wall 32 of the projector with which it is associated and cooperates. The rear end portion of the stop member 45 is formed with a depending lug 50 medially of its transverse edge and this edge is further reinforced by having spaced portions thereof at 51 bent against the inner face of the body to reinforce the structure to provide against distortion and rupture. A coil spring 52 is adapted to be positioned about the depending lug 50 between the reinforcing portion 51 of the top body 45 and the upper face of the top of the projector body 32 to normally bias the stop in a rotational direction about a transverse axis formed by the edge portion 47, so that the stop structure will be canted or biased to cause the clamp element 48 and its wings 48' to bite into the lower face of the top plate 32 to lock the stop member against accidental movement. Movement of the stop member can readily be brought about by pressure on the concave portion 45 against the tension of the spring 52 and when pressure is so applied the forward end will tend to lift and swing on its pivotal point 47 to disengage the biting edges 48-48' of the clamp bar from its frictional engagement with the under face of top wall 32. This structure provides for a quick, convenient operation either forwardly or rearwardly of the stop member to regulate the possible movement of the projector end plate 36 which engages the stop member when moved in a spring compressing direction. It will be noted from Fig. 7 that the bottom of the projector is concave in

cross section by virtue of the angular side wall portions 53 which are joined by the connecting strip 54. A cross brace and wear strip 55 extends transversely of the connecting strip 54 for substantially the greater width of the structure and acts as a wear plate or swivel bearing for the swivel mounting provided by the downwardly extending pin 40.

Transversely of the projector, a projectile stop is provided in the form of a U-shaped pendulum or swing bar, as indicated by reference character 60. This projectile stop has its free ends bent laterally for pivotal support in the side walls 30 of the projector body and normally is free to swing under impact from the projectiles D as illustrated in Fig. 13. The bottom wall 31 of the projector casing has a transverse portion struck out and bent upwardly as at 61 to retain the marbles against travel with the projector plate 36 when the latter is moved in a spring compressing direction. The stop element 61 is just sufficiently high to perform its required function without interfering with the impact plate 36, although the latter is shown as recessed at 62 to provide added clearance in this connection. The pendulum stop 60 is positioned between the side walls 30 just forwardly of the vertical center of the marble or projectile as it descends from the magazine so as to cause the latter to drop backwards instead of forwardly and in the direction of the stop element 61. The magazine is conventional in some features in that it provides a spiral container shown best in Figs. 6 through 12, and indicated generally by reference character E. This container may be of any suitable size to receive and retain the proper number of projectiles and terminates in the central column F which is seated upon an opening provided at the forward end of the projector and indicated by reference character G. The magazine is provided with a pair of depending plates 65 having vertical slots 66 which are received by the guide projections 67 formed at the top of the sidewalls and at each side of the opening G in the projector. The clamp plates 65 are relatively wide and are so spaced as to closely embrace the side walls 30 of the projector and retain the same with the column F in proper vertical alignment with respect to the opening G. Inwardly projecting lugs 66' extend inwardly from the side plates 65 at each side of the medial slot 66 for engagement beneath the edges 67' of the flanges of the top plate 32.

The back wall of the column F is flared outwardly at its bottom as at 68 to provide a rearwardly extending chamber in which is mounted the pivoted trigger 69. Trigger 69 is of plate form and is mounted on transverse pivots 70 in the side wall portions of the bottom of the column within the flared chamber and includes rearwardly extending bottom flange 71 for operative association with the projector plate 36 and forwardly extending supporting extensions 72 which when the trigger normally swings on its pivots move to intercept the next available projectile moving into discharge position as best shown in Fig. 12.

A spring 73 is provided for normally urging the extremity 72 into the position of projectile interception shown in Fig. 12. This spring is shown in Fig. 5 as a hair spring having one extremity hooked in the walls of the slot 66 and the other end engaging the pivoted shaft 70. Other arrangements of suitable spring means may be provided.

Referring to Fig. 1, the pivot opening 23^a for the projector is illustrated as providing for an arcuate movement approximating the area of the playing board. All of the projectors used at the corners will be similarly mounted to provide suitable range in the playing of the various games.

In Fig. 1 panel 1 is shown with a selection of configurations which are suitable for use in association with the playing of certain games to be hereinafter described. The various patterns on the face of the panel embody a

baseball diamond layout indicated by reference character P with the outfield defined at P', and intersecting the outfield is a transverse line Q parallel with the end of panel 1 and intersecting the outer portion of the baseball diamond layout P. The transverse line Q is in fact the chord of the arc R. A similar arrangement is shown at the opposite end of the panel. An additional transverse marker S is provided intermediate the length of the panel and this transverse marker S extends through a circle T positioned centrally of the panel. An additional circle t of greater diameter is formed with the same axis as the smaller circle T and within the larger circle t is the configuration of a square. These configurations define control areas and boundaries and additional layouts may be provided on the surface of the panel for the playing of additional games involving the use of projectiles and a projector. The present application is not intended to disclose all of the possible characteristics of the present type available and is primarily for illustrative purposes in connection with the basic use of the development.

Figs. 16 through 42 illustrate various types of projectiles, targets and hazard objects used in numerous games to be more fully hereinafter described, and it will be noted that the projectiles may be utilized as targets and that one target may be associated with another target or a plurality of targets may be combined to form hazards in intercepting the projectiles delivered by the projector. The projectiles are intended to be of uniform circular size such as shown in Fig. 16 and any commercial marble may be used if of the proper size and weight. The different players may have projectiles of different color to facilitate the playing of the games and to permit proper scoring.

The instant gameboard structure, the projector, the mounting, the projectiles, and the targets are designed for use in playing a large number of games of the type in which speed, skill and experience are required. Many of the games which will be hereinafter described are of such a character as to be suitable in the training of the players in speed, timing, coordination and mathematics. Hereinafter this specification sets forth the playing rules and procedure in connection with certain definite games available by means of this invention. Other games which can be played and for which the present apparatus is particularly adaptable are Simulated Hockey, Race, Simulated Basketball, Bankball, Simulated Tennis, Simulated Skeet, Simulated Handball, Lightning, Simulated Pool, Sly, Simulated Pitch and Catch, Shuffleboard, Mobile Mouse Trap, Convoy, Rub-A-Dub-Dub, Horseshoe, Crokinole, Rotation, Knock-Out, Simulated Volley Ball, Tippy Canoe, Redskins in a Shrimp Boat, Gyro, Drain Pipe and other similar games. The markings on the surface of the gameboard can be altered to suit the playing of additional games and the fact that the magazine is removable from the projector permits the use of the latter with the player inserting the projectiles rather than having the projectiles fed from an automatic magazine such as is provided. The magazine is readily removable and when placed in position, the controlling elements for the projectiles are available for application and use without any adjustment or manipulation.

The entire structure of the playing assembly is available for modification as by removal of the bins B and B', shifting of the projector from the longitudinal center of the end guardrails to the corner guardrails, the removal or connection of the magazine, and such features can be quickly accomplished when changing from one game to another.

The foregoing will be apparent from a discussion of the general rules of the game to follow hereinafter, and also by an analysis of the specific games to be described.

In order to make clear the function of the salient structural features of the game apparatus herein described, certain instructive examples of the many games that may be

played with this apparatus will be described. It is to be understood that these games are described as illustrative examples and do not limit the scope of use of the invention. In preparing the game apparatus for any of the games hereinafter described, it is to be understood that in each game the game board pockets are emptied of all partitions 9 and bankboard sections B and B' unless there is a specific statement to the contrary with reference to the particular game being described. Each of the removable rail sections 12, which when in their proper places on the game board establish connection between the lateral or side guard or bounding rail 2 and the end guard or bounding rail 7 at each corner of the game board are referred to as corner gates. Each of the removable rail sections at the center of each of the end bounding or guard rails are referred to as central gates. When any of said corner or central gates are installed on the game board in its proper place so that it establishes continuity of the bounding rail at that point, said gate will be referred to as being in place. When any of said corner or end gates are not in place they will be referred to as being removed from the board. It is to be understood that all gates are in place in the description of the games hereinafter to appear except those gates which are specifically described as being removed with reference to the game under consideration.

When the pin 40 on the bottom of a projector A is introduced into one of the sockets 23^a provided near each corner of the playing surface, the muzzle of said projector pointing toward the playing surface, said projector will be referred to as being mounted at a corner socket; when the pin 40 on the bottom of a projector A is introduced into one of the sockets 23 located at the center of the end members of the game board, the muzzle of said projector pointing toward the playing surface, this projector will be referred to as being mounted at a central socket. When a statement is made that the power selector of a projector A is positioned at the first line on the power selector scale 42, it is to be understood that the leading edge toward the muzzle of said power selector aligns with the first line on the power selector scale, counting from the muzzle and the same relationship applying for all ordinal numbers from first to sixteenth.

In any of the games hereinafter described, unless specific statement to the contrary is made with reference to some particular game, all the projectors A used in said game may be used with their respective repeated magazines E attached, all said projectors may be used without their magazines attached, or some of said projectors may be used with and some without magazines attached, depending upon agreements made between or among the players before the beginning of play.

On the playing surface of the game board are inscribed three transverse lines Q and S, each of which extends completely across the playing surface from one lateral bounding rail to the other, said transverse lines dividing the playing surface into four areas or zones. The central of the three transverse lines S lies at the transverse center of the playing surface dividing the playing surface into two equal halves. When two players are seated at the game board, one at each end, the pocket 17 of the game board nearer a given player is referred to as that player's pocket and the half of the playing surface between the transverse central line S and a given player's pocket is referred to as that player's half of the playing surface. The area of the playing surface between a given player's pocket and the nearest to said pocket 17 of said transverse line S will be referred to as that player's end zone. The area between a given player's end zone and the transverse central line S will be referred to as that player's central zone and the two areas between the two end zones will be referred to as the central zone.

Each time the game board is set up for play, the playing surface should be made as nearly level as possible by placing sheets of paper or cardboard under any corner

that is low. This is particularly important in games where a rolling target is used.

Certain general rules apply to all or nearly all of the games to be hereinafter described. These general rules will be outlined before a detailed description is given of specific games, and it is to be understood that the following general rules apply to each of the games hereinafter described except when specific deviation from the general rules is pointed out in the descriptive matter relating to one of the games. In the description of the games, the act of projecting a projectile from a projector will be referred to as shooting.

Before play begins each player receives a definite number of projectiles, for instance twenty, and all other projectiles are removed from the game board. A player may store his projectiles in the game board pocket 17 at his end of the game board, in a box placed on the table near his end of the game board and the boxes B and B' serve well for this purpose, in his hand, or in the repeater magazine E of the projector A, if said repeater magazine E is mounted on the projector, but he may not store his projectiles on the playing surface. After play has begun, projectiles shot from the projectors A may come to rest on the playing surface or in the pockets 17 at the ends of the playing surface. To reload his projector, a player may pick up projectiles from the playing surface, from the pocket 17 at his end of the game board, or from any box in which he may be storing his initial allotment of projectiles, but he must not pick up projectiles from the pocket 17 at his opponent's end of the game board, from any box in which his opponent may be storing projectiles, or from the stock of extra projectiles that was not doled out to the players before the beginning of the game.

In starting certain games, it is desirable that both players begin to shoot simultaneously. In such games, if a third person is present to act as referee, the game is started as follows: the target objects are placed upon the playing surface in their starting positions and after both, or all, players indicate they are ready, the referee starts the play by calling "Shoot." After the referee calls "Shoot," each player is free to shoot projectiles at the target or targets as frequently as he wishes. If a third person is not present, one of the players calls, in even cadence, "one, two, three, shoot!" After the word "shoot" each player is free to shoot at the target or targets as rapidly as he wishes. In starting other games, it is desirable that one of the players shoot first. The player who thus initiates play will be referred to as the starter. In such games, chance means are used to determine which player shall have the privilege of naming the starter. The chance means of selecting the starter preferred for use in the game apparatus is as follows: the eccentrically weighted ellipsoidal or egg shaped object of Fig. 34 is placed upon the playing surface and an angular velocity is imparted to it by one of the players. When the ellipsoid comes to rest, one end of its longest diameter will be higher than the other end of its longest diameter because of the eccentric position of the center of gravity of the ellipsoid. Unless the longest diameter of the ellipsoid comes to rest in an orientation perpendicular to the lateral, longitudinal rail, the higher end of the longest diameter will be closer to one end of the game board than will the lower end of the longest diameter. The player at the last mentioned end of the board will have the privilege of naming which player shall be first starter. If the ellipsoid comes to rest with its longest diameter perpendicular to the lateral bounding rails it is spun again. After determining that all other players are ready, the player named starter initiates play by making the first shot. Play then progresses in one of two general manners, depending on the game. In certain games, each player is permitted to shoot as fast as he wishes as soon as the first projectile leaves the barrel of the starter's projector A. In other

games the players shoot in turn, each player taking as much time for each shot as he feels advisable.

If a target object is knocked off the game board over the lateral bounding rail 2 time out is called until said object is returned to the playing surface adjacent to the lateral bounding rail 2 at the point where said object went over said rail. When said object is placed on the playing surface, the main axes of said object are given the same orientation to the main axes of the game board that said group of axes bore to each other when said object was in starting position before play began. For example, if at the beginning of a game a cylindrical disc, such as shown in Fig. 22, is placed on its rounded surface at the intersection of the longitudinal and transverse centers of the board with its flat surface parallel to the lateral bounding rails 2, and said disc be knocked over the lateral bounding rail 2 during the progress of play, said disc is returned to the playing surface adjacent to the lateral bounding rail 2 at the point where said disc went over said rail, said disc being placed on its rounded surface with its flat surfaces parallel to the lateral bounding rails 2. After a target object has been knocked out of bounds and has been returned to its proper position, the player or team opposing the player or team who knocks the target object out of bounds reinitiates play by making the first shot, other rules pertaining to the resumption of play being the same as the rules for initiating play at the beginning of the game. If it cannot be determined who knocked the object out of bounds, the player whose projector A is nearest the object when it is returned to the playing surface takes the first shot. If, while playing a given game, a player causes any object, except the game apparatus parts used in playing that particular game, to contact any target object upon the playing surface, or if a player causes a target object to move by any means other than by shooting a projectile from his projector, or if a player interferes with the normal course of a projectile from an opponent's projector by any means other than by shooting a projectile from his projector, a foul is called. When a foul is called all target objects are returned to the positions they held immediately before the foul was committed. The player or team responsible for the foul is then prohibited from shooting any projectiles until the opposing player or team has executed three shots. As soon as the projectile leaves the barrel in the third of a series of foul shots, both teams resume play as before the foul was committed. If, however, a player or team scores on the first or second of the three shots, the damage is considered repaired and play is resumed as before the foul was committed, the uncompleted foul shots being forfeited.

In every game hereinafter described, unless there is specific statement to the contrary, a projectile may be caromed off the bounding rails 2 and 7 at any point. In most games, if one player wins consistently, the power selector of the less expert player should be moved back away from the muzzle by progressive small steps until the games are close matches. Players should exchange their positions at the game board at the end of each game. If the end of a game is determined by time, the game may be divided into two half periods, say of five minutes each, and the players may exchange positions at the game board at the end of each half.

The following description of games are examples of the many games that may be played with this apparatus.

Simulated baseball

Two players seat themselves at opposite ends of the game board. The two central gates 20 are removed, and a projector A is mounted at each of the two central sockets 23. The power selector of each projector A is positioned at the fourth line on the power selector scale 42. The repeater magazines E must be removed from the projectors A.

In each pocket 17 are placed six partitions 9, one par-

tition being inserted in each of the pairs of grooves 5 and 8 in longitudinal alignment with the triangular markings imprinted near the edge of the playing surface adjacent said pocket 17, thus dividing each pocket 17 into seven sub-divisions, a central sub-division and three lateral sub-divisions between the central sub-division and each of the lateral bounding rails 2.

All projectiles used in simulated baseball are spherical, such as shown in Fig. 16. At the beginning of each half of each inning, the player representing the fielding team is allotted five white projectiles representing baseballs and hereinafter referred to as balls, and ten projectiles of another color. The player representing the batting team is allotted ten projectiles, none of them white. In the pocket 17 at the batting team's end of the game board, the space in the central subdivision and the first divisions lateral to the central subdivision represents the strike zone. To pitch, the player representing the fielding team places a white ball in his projector A and, when his opponent is ready, shoots said ball toward his opponent's pocket 17. If said pitched ball enters the strike zone, it counts as a strike. If the player representing the batter, hereinafter referred to as the batter, shoots at said pitched ball and misses it, it is counted as a strike. If the batter does not shoot at the pitched ball and it enters a second subdivision lateral to the central subdivision, it counts as a ball. If the batter does not shoot at a pitched ball, and said ball comes to rest in one of the third sub-divisions lateral to the central subdivision, it counts as a wild pitch and each base runner advances one base. If the batter does not shoot at a pitched ball, and said pitched ball comes to rest on the playing surface it is counted as a ball unless the batter chooses to shoot at it. If the batter shoots a projectile at a pitched ball and said projectile contacts said ball, the batter will be said to have batted the pitched ball and after its contact with the batter's projectile, the pitched ball will be referred to as a batted ball. If a batted ball rolls into the batter's pocket or contacts one of the lateral bounding rails 2 in foul territory on the baseball field inscribed on the batter's half of the game board, the batted ball counts as a foul ball. After a batted ball has contacted one of the lateral bounding rails in foul territory on the baseball field inscribed on the batter's half of the game board, said batted ball may not be fielded. The fielding of a batted ball will be hereinafter fully discussed. If a batted ball contacts one of the lateral bounding rails 2 on the batter's half of the playing surface, but in fair territory on the baseball field inscribed on the batter's half of the game board, said batted ball is considered an infield fly and an automatic out, provided first and second bases or all three bases are occupied by baserunners and provided there are not already two outs. If the batting team does not have baserunners on both first and second bases, or if there are two outs, the player representing the fielding team must field the ball successfully or the batter advances to first and any baserunners on already advance one base. If said batted ball is not an infield fly, and said batted ball is successfully fielded, the batter is out and no baserunner advances.

If a batted ball contacts one of the lateral bounding rails 2 on the fielding team's half of the game board, said batted ball will be considered a scratch single unless it is subsequently fielded, and each base runner will advance one base. If said batted ball is subsequently fielded, it will be considered a sacrifice, and the batter is considered out, but each baserunner on base will advance one base. If a batted ball enters one of the third sub-divisions lateral to the central subdivision of the fielder's pocket 17 without first contacting one of the lateral bounding rails 2, said batted ball is considered a single, and the batter advances to first base. Any baserunner on first base advances to third and all other baserunners score. If a batted ball enters one of the second sub-divisions lateral

to the central subdivision of the fielder's pocket 17 without first contacting one of the lateral bounding rails, it is considered a double. The batter advances to second and all other baserunners score. If a batted ball enters one of the first subdivisions lateral to the central subdivision of the fielder's pocket 17 without first contacting one of the lateral bounding rails 2, the batter advances to third base and all other base runners score. If a batted ball enters the central subdivision of the fielder's pocket, it counts as a home run. If, before a batted ball contacts one of the lateral bounding rails 2, the ball comes to rest on the playing surface in fair territory with respect to the baseball field inscribed on the batter's half of the playing surface, the ball counts as a bunt, and all runners on base advance one base. Unless a bunt is subsequently fielded, the batter advances to first. If the bunt is fielded, the batter is out.

To field a batted ball, the fielder shoots one projectile at said batted ball. If the projectile contacts the batted ball before the ball has rolled into a pocket 17, the fielder is said to have fielded the ball, and the ball is no longer referred to as a batted ball, but must be called a fielded ball. If any batted ball rolling on the playing surface is fielded before the batted ball has contacted one of the lateral bounding rails 2, the batter is out and no base runner may advance. If there are any runners on base, and a ball is fielded so perfectly that the ball rolls into the batter's pocket 17, it counts as a double play and the most advanced baserunner is retired from the base paths. If a fielded ball is rolling toward the batter's pocket 17, the batter may shoot one projectile at it in an attempt to prevent said fielded ball from entering said batter's pocket 17. A fielder may use his projector barrel to prevent a batted ball from entering the central subdivision of his pocket 17, provided said projector is properly mounted in its socket. When a batted ball contacts the fielder's projector the batter is not out, but the fate of the batter and the other baserunners is determined by the subsequent course of the batted ball, all of the foregoing rules applying.

As in baseball, three strikes constitute an out; a foul ball counts as a strike unless there are already two strikes on the batter; and three outs retire a side. Four balls entitle a batter to go to first base and each team bats in each inning and the team with the highest score at the end of nine innings wins. In case of a tie at the end of nine innings, additional innings are played until at the end of some inning one team leads. If so desired, the power of each team's projector may be varied at the end of each half inning, decreasing the power of the fielder's projector A or increasing the power of the batter's projector A makes for a higher batting average. These power relationships should be so adjusted that each player bats between .300 and .400. Players may make their own rules governing the use of the power selector in playing simulated baseball.

Flipsydoode

Two players seat themselves at opposite ends of the game board. The two central gates 20 are removed and a projector A is mounted at each of the two central sockets 23. The power selector of each projector A is positioned at the seventh line on the power selector scale 42.

In each pocket 17 are placed six partitions 9, one partition 9 being inserted in each of the pairs of grooves 5 and 8 in longitudinal alignment with the triangular markings imprinted near the edge of the playing surface 1 adjacent said pocket 17, thus dividing each pocket 17 into seven subdivisions, a central subdivision and three subdivisions between the central subdivision and each of the lateral bounding rails 2. In each pocket, each of the first subdivisions lateral to the central subdivision counting from the central subdivision toward each of the

lateral bounding rails, will be referred to as a first subdivision lateral to the central subdivision. Each of the second subdivisions lateral to the central subdivision, counting from the central subdivision toward each of the lateral bounding rails 2, will be referred to as a second subdivision lateral to the central subdivision. Each of the subdivisions adjacent to each of the lateral rails 2 will be referred to as a third subdivision lateral to the central subdivision. This terminology will be used not only with reference to this specific game, but with reference to all games hereinafter described where one or each of the game board pockets 17 is partitioned into seven subdivisions. The target object comprising two parallelepipeds joined by a flat, flexible connecting band and as illustrated in Fig. 37 will be hereinafter referred to as the twin-wedge. The twin-wedge is placed at the center of the playing surface, each parallelepiped resting on one of its rectangular faces adjacent to said connecting band, so that the band is also resting on the surface of the game board, said twin-wedge being so positioned that its longitudinal axis lies parallel to the lateral bounding rails 2 and its flexible connecting band lies on the center of circle T inscribed on the surface of the game board. One of the oblong target objects resembling castle ramparts, and as shown in Fig. 30, is placed upon said connecting band, the bottom of said oblong target object resting on said band, the longitudinal axis of said oblong target object lying at right angles to the longitudinal axis of the twin-wedge, and the centroid of said oblong target object lying in the same vertical line with the centroid of the twin-wedge. In the groove atop said oblong target object, directly above the centroid of said oblong target object, is placed one of the heavier target balls, such as is shown in Fig. 17. The set-up for this game is shown in place in Fig. 3.

Each player is allotted ten spherical projectiles, as shown in Fig. 16, which he must store in a box near his end of the game board. All other projectiles are removed from the game board. A player may load his projector A only with projectiles taken from said box near his end of the game board, and he may shoot each of his projectiles only once. By chance means it is determined which player shall shoot first. Players alternate shots. It is the object of each player to cause as many projectiles as possible to roll from the playing surface into his own pocket 17, and to have the projectiles as near the longitudinal center of the game board as possible. If a player turns his projector to a sharp angle and shoots a projectile slowly from said projector so that the projectile drops directly into the pocket without first rolling on the playing surface, the projectile is removed from its resting place in the pocket and placed in the central subdivision of his opponent's pocket. In order to cause a projectile to return to his own pocket, a player gently shoots the projectile under the elevated edge of the parallelepiped facing him. The inertia of the projectile lifts said parallelepiped and the weight of the parallelepiped causes the projectile to roll back toward the pocket of the player who shot the projectile. If a player misses the parallelepiped, and his projectile rolls into his opponent's pocket, that projectile will count for his opponent when the score is totalled at the end of the game. If a projectile comes to rest on the playing surface, it is permitted to remain there and if the projectile is subsequently knocked into one of the pockets, it counts for the player in whose pocket it comes to rest. If any player knocks the ball from its resting place atop the oblong target object, that player forfeits the game to his opponent.

The game terminates when each player has shot all of his ten projectiles. Each projectile in one of the pockets counts for the player in whose pocket it rests. In each pocket, each projectile in the central subdivision counts four points, each projectile in each of the first subdivisions lateral to the central subdivision counts three

points; each projectile in each of the second subdivisions lateral to the central subdivision counts two points; each projectile in each of the third subdivisions lateral to the central subdivision counts one point. The player with the higher score wins.

Naval engagement

Two players seat themselves at opposite ends of the game board. The two central gates 20 are removed, and a projector A is mounted in each of the two central sockets 23. The power selector of each projector A is positioned at the eleventh line on the power selector scale 42. One of the end bankboard sections B' is placed in each end of each pocket 17, the central portion of each pocket 17 remaining empty of bankboards and partitions. Each player receives ten projectiles, as shown in Fig. 16, none of said projectiles being red. Each player is assigned one of the model boats, illustrated in Fig. 29, each boat being a different color to permit said boats to be distinguished from each other. Each player places his boat on its bottom surface on the infield of the baseball diamond inscribed on his half of the playing surface, the prow of said boat resting on the second base, the stern resting on the pitcher's mound, and the longitudinal axis of the boat being exactly parallel to the lateral bounding rails 2. Each player receives four red balls, representing torpedoes. Each player places two of his balls in the longitudinal groove atop his boat, one red ball being placed in the fore depression in the longitudinal groove and one red ball being placed in the aft depression in the longitudinal groove. Each player holds two red balls in reserve. The set-up for this game showing the targets in position for play is shown in Fig. 4.

If a boat with two balls in the longitudinal grooves is struck a blow of suitable force on its side a beam to one ball, that ball will be ejected from the boat over the opposite side of the boat from the side on which the boat is struck, and the ball will travel in a course substantially perpendicular to the line of the longitudinal axis of the boat immediately before the moment of impact. If a boat with two balls in the longitudinal groove is struck a blow of suitable force on the side at a point equidistant from the two balls, both of said balls will be ejected over the side of the boat opposite the side on which the boat is struck, and each of the balls will travel in a course substantially perpendicular to the line of the longitudinal axis of the boat immediately before the moment of impact. If a single ball is at rest in the longitudinal groove atop a boat, and said boat is struck a blow of sufficient force to eject said ball over the side of the boat opposite the side on which the boat is struck, the course of travel of the ball will depend on the position of the point of impact. If the blow is struck at a certain point between the center of the ball and the center of gravity of the boat, the ball will travel a course substantially perpendicular to the line of the longitudinal axis of said boat immediately before impact. If the blow is struck a relatively short distance aft from said certain point, the ball will follow a course diverging forward from a line perpendicular to the line of the longitudinal axis of the boat immediately before the moment of impact. If the blow is struck a relatively short distance forward of said certain point, the ball will follow a course diverging aft from a line perpendicular to the line of the longitudinal axis immediately before the moment of impact. If the blow is struck a relatively large distance from said central point, the results are unpredictable.

At a given signal, each player begins to shoot as frequently as he wishes. It is the object of each player to cause the red balls in his own boat to be ejected from their resting place in the boat and to contact his opponent's boat before contacting any other object upon

the playing surface. When a red ball ejected from one player's boat contacts his opponent's boat before contacting any other object on the playing surface and before contacting one of the lateral bounding rails 2, said 5 opponent's boat is said to be torpedoed. If a ball ejected from one player's boat contacts his opponent's boat after having first contacted some other object on the playing surface, or after having contacted one of the lateral bounding rails 2, said opponent's boat is not considered to be torpedoed, as the other object or rail is considered to have exploded the red ball representing a torpedo. When any given boat has been torpedoed five times, the boat is considered to be sunk, and the opponent of the owner of the "sunk" boat wins the game.

10 15 When a torpedo ejected from the opponent's boat is rolling toward a player's boat, said player may attempt to knock his boat out of the path of the torpedo, or he may attempt to eject a torpedo from his own boat in such a manner that it contacts his opponent's torpedo and explodes it before the torpedo contacts his boat. A player may not, however, shoot a projectile from his projector at a live torpedo. If a player shoots a projectile and before the projectile either comes to rest or contacts some other object on the playing surface it 20 25 contacts a torpedo ejected from his opponent's boat before said torpedo has contacted any other object on the playing surface, the player's boat will be considered torpedoed. When a player has ejected both torpedoes from his boat it is necessary for him to "sail through dangerous waters" to replenish his supply of torpedoes. When a player's boat is emptied of torpedoes, he must propel his boat to a position where some portion of the boat lies in his opponent's end zone, and then he must 30 35 propel the boat back toward his own end of the game board until some portion of the boat lies in his own end zone. When this has been accomplished, he must return his boat to its exact starting position and place two torpedoes in the boat. If the player does not have two red balls in his possession, his opponent is 40 required to surrender the required number of red balls immediately. To propel his boat from his opponent's end zone toward his own end zone, a player caroms his projectiles off one of the bankboards B' at the opposite end of the game board or off a lateral bounding rail 2 and a bankboard B'. While a player is maneuvering to reload his boat, his opponent may at any time torpedo 45 50 55 said boat. A player may not shoot a projectile directly at his opponent's boat, nor may a player attempt to carom a projectile from a bankboard B' or from a lateral bounding rail 2 in such a way that the projectile contacts the boat of his opponent before the projectile contacts some other object on the playing surface. If a player shoots a projectile and the projectile contacts the opponent's boat before it contacts some other object on the playing surface, said player commits a foul. If at the time of the illegal contact the boat contains two torpedoes, the boat and torpedoes are returned to their respective positions at the time of the illegal contact and the player who committed the foul may not 60 65 70 shoot again until the owner of the boat has shot ten projectiles. If at the time of the illegal contact the boat contained one torpedo, the boat and torpedo are returned to their respective positions at the time of the contact, and the owner of the boat places one more torpedo in his boat. The player who committed the foul may not shoot again until the owner of the boat has shot five projectiles. If at the time of the illegal contact the boat contains no torpedoes the owner of the boat is permitted to return it to its starting position and place two torpedoes in the boat. As was previously stated, the first player to torpedo his opponent's boat five times is the victor in the naval engagement. If one player wins consistently, the boat of his opponent should 75 be considered a more sturdy craft requiring six or seven,

or eight torpedoes to sink it, or whatever number makes the closest contest.

Battle of the bridge

Two players seat themselves at opposite ends of the game board. The two central gates 20 are removed, and a projector A is mounted at each of the two central sockets 23. The power selector of each projector A is positioned at the fourth line on the power selector scale 42.

Three of the target objects comprising rectangular parallelepipeds, as shown in Fig. 35, are placed on the playing surface inside the circle t inscribed on the playing surface, each parallelepiped resting on one of its square faces with its vertical faces being either parallel to or perpendicular to the lateral bounding rails 2, and its center of gravity lying directly over the transverse center line S of the playing surface. One of the parallelepipeds is positioned on line S with its center of gravity directly over the center of the circles T and t inscribed at the center of the playing surface. One of the remaining parallelepipeds is positioned to each side of the central parallelepiped, two of the lateralward corners of each of the remaining parallelepipeds touching the line demarking the circumference of circle t inscribed on the playing surface. On top of each of the three parallelepipeds another rectangular parallelepiped is placed, resting on one of its square faces, its vertical faces aligning with the vertical faces of the parallelepiped on which it rests, thus forming three stacks of two parallelepipeds each. Spanning each of the spaces between the central stack and each of the lateral stacks of parallelepipeds atop said stacks, is placed one of the oblong target objects resembling castle ramparts, as shown in Fig. 30, with its longitudinal axis lying directly above the central transverse line S of the playing surface and the two oblong objects touching each other at a point directly above the center of the circles T and t inscribed on the playing surface. Two more of the oblong target objects are placed upon the playing surface, one lateral to and touching each of the lateral stacks of parallelepipeds, the longitudinal axes of the two objects lying directly over the transverse central line S of the playing surface. This configuration of objects, which is shown in Figs. 43 and 43^a, is designed to represent a bridge of two spans, the stacks of parallelepipeds representing the piers and the oblong objects atop said stacks representing the spans of the bridge. Each of the two oblong objects placed atop the stacks of parallelepipeds will be referred to as a span in the description of the game hereinafter to appear.

Each player receives a model boat, as shown in Fig. 29, which he places on the playing surface anywhere in his own end zone, the boat resting on its bottom surface. It is most advantageous to place the boat with its longitudinal axis lying directly above the straight line between the central socket 23 at its own end of the board and the center of the space between the central stack of parallelepipeds and the lateral stack of parallelepipeds at his right as he faces the game board with the stern of the boat facing his own projector and the prow of the boat touching the transverse line separating his own end zone from the central zone. The object of each player is to propel his boat under the span to his own right as he faces the game board, and then to propel his boat as far as possible toward his opponent's pocket 17 by shooting projectiles under the span. If a player propels his boat under the span to his right, and then causes a projectile to strike said boat without the projectile first passing under the span, the player loses a point. When a player has propelled his boat as far as he can or as far as he wishes, he knocks down the bridge to prevent his opponent from propelling his boat further toward the pocket 17 opposite the opponent, and play terminates until all objects are returned to their starting positions.

One player is selected by chance to play first. Players

alternate turns. At each turn a player may either shoot one projectile or move his projector A from one socket at his own end of the game board to another socket at his own end in order to shoot at his boat from a more advantageous angle, but he cannot execute both said maneuvers at the same turn. A player may not shoot directly at his opponent's boat. If a projectile fired by any player contacts the boat of his opponent before it contacts said player's boat, he loses two points. If a player knocks the span to his right off the stacks of parallelepipeds before he has propelled his boat under the span, he may not shoot again until the bridges are returned to their starting positions, and his opponent may shoot repeatedly at his own boat until such time as one of his projectiles does not contact his boat, at which time play terminates until all objects are returned to their starting positions. If, before he has propelled his boat under the span to his right, a player knocks the span to his left off the stacks of parallelepipeds so that a boat may not pass under the span without touching said span, the player loses two points, and play terminates until all objects are returned to their starting positions. If at any time a span falls on a boat, or touches a boat in any way, said boat is considered sunk and the owner of the boat cannot make a positive score until after all objects have been once more returned to their starting positions. When play terminates any boat that has not touched one of the bridge spans since all objects were last placed in their starting positions will score one point for the boat's owner if it lies wholly in the central zone of the owner's opponent; two points if the boat lies partly in the central zone of owner's opponent and partly in the end zone of the owner's opponent; three points if the boat lies wholly in the end zone of owner's opponent; and five points if it lies in the pocket 17 of owner's opponent. Each time all objects are returned to their starting positions, play is resumed as at the beginning of the game, the players alternating as starter. The game is terminated when a player attains a score of five or minus four. A player attaining a score of five wins. A player attaining a score of minus four forfeits the game to his opponent.

Trucking to market

Two teams of two players each seat themselves at the game board, one player at each corner, and partners being at corners diagonally opposite each other. Each of the corner gates 12 is removed and a projector A is mounted at each of the corner sockets 23^a. The power selector of each projector A is positioned at the tenth line on the power selector scale 42. The players at one end of the game board represent produce retailers, and the players at the opposite end of the game board represent produce wholesalers. Before play begins, each retailer receives a truck, shown in Figs. 41 and 42, each truck being marked with distinctive indicia to permit it to be distinguished from the other truck. Each wholesaler is allotted four red balls representing sweet potatoes, which the wholesaler should store in a box near his corner of the game board and each player is allotted fifteen spherical projectiles. Each retailer places his truck in the retailer's end zone to said retailer's side of the longitudinal center of the game board, the front of said truck facing toward the retailer's partner. In each channel on the under face of his truck, each retailer places two projectiles representing wheels, thereby raising the chassis of the truck above the playing surface. Fig. 44 illustrates the set-up on the game board for the playing of this game.

It is the object of each team to drive its truck from its starting position into the half of the wholesaler's end zone nearest the wholesaler of said team, to load the truck with wholesaler's four "sweet potatoes" and then to drive the truck back into the half of the retailer's end zone from which it started. The team that accomplishes these maneuvers first, so that the retailer of the team can "beat his competitor to market" with the sweet po-

tatoes wins. To drive the truck, the player behind the truck shoots projectiles at the frame of the truck, and the player in front of the truck shoots projectiles into the channels under the truck in order to keep at least one projectile in each of the channels. As the truck is rolled along it will roll off the projectiles originally placed in said channels. If a team permits one channel of the truck to become empty of projectiles, the truck is considered to have a flat tire and the member of the team away from whom the team is attempting to drive the truck is not permitted to shoot again until the member of the team toward whom the team is attempting to drive the truck has shot at least one projectile into the empty channel so that there is at least one projectile in each channel. If a team permits both channels of its truck to become empty of projectiles so that the entire chassis of the truck rests directly on the playing surface, the truck is considered to be a total wreck and the team forfeits the game to the opposing team.

When a truck is being driven from the retailer's end zone to the wholesaler's end zone, the front of the truck must at all times be nearer to the wholesaler's pocket than the back end of the truck. If, while the truck is being driven from the retailer's zone to the wholesaler's zone, the truck turns so that the back end of the truck is nearer to the wholesaler's pocket than the front of the truck, the retailer of the team to whom the truck belongs may not shoot again until the wholesaler of the team turns the truck so that its front end is once more nearer the wholesaler's end zone than the rear end. As soon as a team has driven its truck into the half of the wholesaler's end zone nearest the wholesaler of the team, the wholesaler may put his four "sweet potatoes" into the back of the truck and the team may begin to drive the truck back to the half of the retailer's end zone from which it started. The truck may be backed from the wholesaler's end zone into the wholesaler's central zone, but when the truck is being driven toward the retailer's end zone and any part of the truck lies in the retailer's central zone, the front end of the truck must be nearer to the retailer's pocket than the back end of the truck, or the wholesaler of the team owning the truck cannot shoot until the retailer of the team has turned the truck so that it fulfills this condition.

If any player shoots at a time when he is forbidden to shoot by the foregoing rules, neither player of said player's team may shoot again until the opposing team has executed fifteen shots.

If, while in transit, one or more "sweet potatoes" is knocked out of a truck, the sweet potatoes must be returned, and the players of the team owning the truck may not shoot again until the players of the opposing team have executed ten shots. A player may not shoot directly at the opponent's truck. If a player shoots a projectile and the projectile contacts the opponents' truck before contacting the truck belonging to said player's team, or before contacting another projectile, neither member of said player's team may shoot again until the members of the opposing team have executed ten shots. To initiate play at the beginning of the game, a signal is given by one of the players or by a fifth individual, and at the given signal each player begins to shoot as frequently as he wishes.

Simulated dodge ball

Two players seat themselves at opposite ends of the game board. The central gates 20 are removed and a projector A is mounted in each of the central sockets 23. The power selector of one projector A is positioned at the first line on the power selector scale 42. The power selector of the other projector A is positioned at the sixth line on the power selector scale 42. The player with the projector set for the higher power will be referred to as the dodger. The dodger arranges nine discs, such as shown in Fig. 22, each on one of its flat surfaces on the

line Q that separates his end zone from his central zone. The nine discs may be arranged in any desired pattern so long as some part of one of the flat surfaces of each disc touches the playing surface on each side of the line Q. The set-up of target objects for playing this game is shown in Fig. 45.

It is the object of the player with the projector set for lower power, who will be hereinafter referred to as the thrower, to cause projectiles fired from his shooter 10 to contact the discs arranged in front of the dodger's projector. It is the dodger's object to prevent the thrower's projectiles from contacting the discs by knocking the discs out of the path of the projectiles. The dodger may not shoot a projectile directly at a projectile shot by 15 the thrower. If a projectile shot by the dodger contacts a projectile shot by the thrower without first having contacted a disc, the thrower is entitled to remove from the playing surface the disc of his choice. When the dodger is ready, the thrower starts the game by shooting a single 20 projectile at one or more of the discs. Each disc that is touched by the projectile shot by the thrower is removed from the playing surface. If projectiles come to rest on the playing surface, they are removed from the playing surface before the thrower again shoots. All 25 discs that were not touched by the thrower's projectile are permitted to remain where they came to rest, whether it be on the playing surface or in one of the pockets. When the dodger indicates that he is ready, the thrower shoots a second time, the same rules applying. This 30 process continues until all the discs have been removed from the playing surface because of contact with one of the thrower's projectiles, or shot from the playing surface by the dodger in an effort to knock them out of the path of one of the thrower's projectiles. The number of 35 shots fired by the thrower before the playing surface is emptied is the thrower's score. The players then exchange positions at the ends of the game board, allowing the projectors A to remain at their original positions. The nine discs are again placed on the playing surface, as heretofore described, and the process is repeated, the former dodger now being the thrower, and the former thrower now being the dodger. The player with the lower score wins the game. If one player consistently wins, his opponent is given progressively more power 40 when acting as thrower on until the games are close matches.

Melee

Two players seat themselves at opposite ends of the 50 game board. The two central gates 20 are removed and a projector A is mounted at each of the two central sockets 23. The power selector of each projector A is positioned at the fifth line on the power selector scale 42. Before play begins, an odd number, greater than 55 one, of target objects are placed upon the transverse center line S of the playing surface. This starting position for target objects is used whether play is initiated by both players at a given signal or by one player acting as starter.

The object of each player is to drive as many as possible of the target objects into the pocket 17 at his 60 opponent's end of the playing surface. Once the play has started, each player shoots as rapidly as he can or wishes. When all target objects have been driven into the pockets 65 17, the game is ended. Each target object in a given pocket counts one point for the player at the opposite end of the game board. High scorer wins.

In a preferred form of Melee, nine discs are spaced along the transverse center line S of the playing surface, 70 each on its convex surface, and each with its flat surfaces parallel to the lateral bounding rails 2. A set-up showing target objects in place for the playing of this game is illustrated in Fig. 46. Because a disc will roll farther as a result of an impact of any given force if it is so 75 oriented that it will roll in line with the path of the

projectile that strikes it, and because any disc resting on its convex surface will move more readily than a disc that has been knocked upon its flat surface, a player's shots will be much more effective if he selects his targets judiciously and often a shot caromed off the lateral bounding rail 2 will be more effective than a shot aimed directly at the target. Thus expert play entails alertness and quick thinking as well as hand-eye coordination and manual dexterity.

Siege

Two players seat themselves at opposite ends of the game board. The two central gates 20 are removed, and a projector A is mounted at each of the two central sockets 23. The power selector of the projector A of one player, hereinafter referred to as the attacker, is positioned at the third line on the power selector scale 42. The power selector of the projector A of the other player, hereinafter referred to as the defender, is positioned at the tenth line on the power selector scale 42. The defender arranges seven of the oblong target objects, as shown in Fig. 30, and hereinafter referred to as ramparts, along the arc inscribed on the playing surface in his own central zone, the longitudinal axis of each rampart being tangentially oriented with respect to the arc, said ramparts being uniformly spaced upon the arc between the lateral bounding rails 2 in such a way that no projectile traveling on the playing surface could pass between any adjacent two ramparts without contacting one of them, as shown set up for play in Fig. 47.

The defender receives one projectile; the attacker receives thirty projectiles, hereinafter referred to as his men, and all other projectiles are removed from the game board. It is the object of the attacker to get as many as possible of his men into the defender's pocket 17 without said men first contacting any of the ramparts. Each of the attacker's men that contacts a rampart is thereby killed, and is removed from the game board. The attacker may shoot each of his thirty projectiles only once. The attacker begins the play by shooting a projectile at the ramparts in an attempt to separate two adjacent ramparts sufficiently to permit a man to pass between them without touching one of them. The defender and the attacker then alternate shots, each player taking as long for each shot as he wishes. The defender, by shooting projectiles at the ramparts, attempts to keep the ramparts in such a position that the attacker is unable to shoot a projectile into the defender's pocket without said projectile contacting one of the ramparts. Before each shot, the defender may remove any of the gates 12-20 at his end of the game board, and mount his projector A at any of the sockets 23-23^a at his end of the game board. At both projector locations not in use, he should put the gates in place so that projectiles will not escape from the game board. After each shot, the defender recovers his projectile and uses it again for his next shot. Play terminates when the attacker has shot all of his thirty projectiles. The number of the attacker's men in the defender's pocket 17 is counted and the resultant number is the attacker's score.

The players then exchange their positions at the game board, the former defender becoming the attacker, and the former attacker becoming the defender and the process is repeated. The player with the higher score wins. If one player wins consistently, the less expert player should be given progressively more power in his turns as attacker until the games are close matches.

Tipstyle

Two players seat themselves at opposite ends of the game board. The two central gates 20 are removed and a projector A is mounted in each of the two central sockets 23. The power selector of each projector A is positioned at the fifth line on the power selector scale 42.

The target object comprising two parallelepipeds, as

shown in Fig. 37, joined by a flat, flexible connecting band will be hereinafter referred to as the twin-wedge. The twin-wedge is placed at the center of the playing surface, each parallelepiped resting on one of its rectangular faces not adjacent to the connecting band, so that the band is raised above the playing surface of the game board and is substantially parallel to that surface, the twin-wedge being so positioned that its longitudinal axis lies parallel to the lateral bounding rails 2 and its flexible connecting band is directly above the center of the smaller circle T inscribed in the center of the playing surface. Three of the oblong target objects, shown in Fig. 30, are now arranged on each side of the twin-wedge and the lateral bounding rails 2, the three oblong objects being arranged to form three sides of a square whose sides are either parallel or perpendicular to the lateral bounding rails 2, the open side of the square facing the twin-wedge and aligning with the longitudinally oriented side of the square V inscribed at the center of the playing surface, the transverse sides of the square, three sides of which are formed by said objects, being equidistant from the transverse central line S. Two projectiles are placed on the top of each oblong object to decrease the distance the objects will be moved by any given impact. The inside of the square formed by the three oblong objects and the longitudinal line inscribed on the playing surface shall be referred to as the goal, and any object will be said to be in said goal if the object rests on the goal and does not touch the longitudinal line inscribed on the playing surface. The arrangement of target objects for the playing of this game is shown in Fig. 48.

At the beginning of the game each player is allotted fifteen spherical projectiles. The projectiles belonging to one player are to be of a color distinct from the color of the projectiles belonging to the other player, so that the projectiles of each player may be readily distinguished. Each player places his projectiles in a box near his end of the game board. A player is permitted to reload his projector A only with projectiles taken from his box. He may shoot each projectile only once, except in the case hereinafter noted. One player is chosen by chance means to shoot first.

The object of the game is to shoot projectiles into the goals. A player must not, however, cause a ball to contact one of the castle ramparts before the ball has contacted the twin-wedge or another projectile. If a ball shot by a player contacts one of the castle ramparts before it has contacted the twin-wedge or another projectile, the player who shot the ball is fined one point and all objects except projectiles are returned to their starting positions. To shoot a projectile into the goals, a player attempts to roll the projectile slowly onto the twin-wedge. If a projectile is rolling at the right speed, the twin-wedge will tip and the flexible band will bend in such a manner that each of the parallelepipeds will come to rest on one of the parallelepiped's faces adjacent to the flexible band, and the flexible band itself will come into contact with the playing surface, and the projectile will either roll laterally from the twin-wedge or remain resting on the flexible band. If the projectile comes to rest on the flexible band, the player who shot the projectile scores one point and is privileged to shoot the projectile again. Except in this case, a player may not shoot a plurality of shots without alternating shots with his opponent.

Whenever a projectile shot by one player comes to rest anywhere except on the flexible band, that player is said to have completed play with that projectile. Each player alternately completes play with a single projectile at each turn. Unless a projectile comes to rest on the flexible band, it may not be shot again. If the projectile rolls laterally from the twin-wedge, it may enter the goal. If a projectile enters the goal, that projectile is removed from the playing surface and the player who originally

shot the projectile scores one point whether the projectile entered the goal before it came to rest after being projected onto the playing surface, or whether it was knocked into the goal by a subsequent shot of either player. After each shot the twin-wedge is returned to its original position.

A player may shoot at one of his own projectiles resting on the playing surface in an effort to knock it into the goal. A player may shoot at an opponent's projectile in an attempt to carom his own projectile off his opponent's projectile and into the goal, or to roll said opponent's projectile into a position where the opponent could not score with his projectile. Play is terminated when each player has completed play with each of his projectiles, and the player with the higher score wins.

Invasion

Two players seat themselves at opposite ends of the game board. The two central gates 20 are removed, and a projector A is mounted at each of the two central sockets 23. The power selector of each projector A is positioned at the seventh line on the power selector scale 42. In each pocket 17 are placed six partitions 9, one partition being inserted in each of the pairs of grooves 5 and 8 in longitudinal alignment with the triangular markings imprinted near the edge of the playing surface adjacent the pocket 17, thus dividing each pocket 17 into seven subdivisions, a central subdivision and three lateral subdivisions between the central subdivision and each of the lateral bounding rails 2.

Each player receives three rectangular parallelepipeds, as shown in Fig. 25, which are distinctively colored to permit them to be distinguished from the parallelepipeds belonging to the other player. All of the parallelepipeds are arranged along the transverse central line S of the playing surface, each resting on one of its square faces with its centroid directly above said line, the vertical faces of the parallelepipeds being oriented at an angle of forty-five degrees to line S, the parallelepipeds of each player alternating with those of the other player so that no two parallelepipeds belonging to any one player are adjacent to each other, this set-up being shown in Fig. 49.

Each player is allotted six projectiles. One player is selected by chance means to shoot first. Players then alternate shots. If a projectile comes to rest on the playing surface it is removed. The object of each player is to drive each of his own parallelepipeds, hereinafter referred to as pieces, into his opponent's pocket 17, as near the center as possible. A player may not shoot directly at an opponent's piece. If a projectile shot by one player contacts one of his opponent's pieces before said projectile contacts one of his own pieces, that player loses five points. Before a player shoots, his opponent may pivot his projector A to any desired angle in order to make it more difficult for the player to knock one of his pieces into the central subdivision of the pocket 17 at opponent's end of the game board. After a player has shot, before he removes his hands from his projector, he must position his projector in the position he wishes it to remain during his opponent's turn. After a player removes both hands from his projector, he may not touch it again until his opponent has shot and his opponent's projectile has come to rest. A player may not shoot until his opponent has removed his hands from the projector. The game terminates when one player has knocked all of his own pieces into his opponent's pocket 17. If a player knocks one of his opponent's pieces into said opponent's pocket, the player forfeits the game to his opponent. A piece resting in a central sub-division of one of the pockets 17 counts ten points for its owner. A piece resting in one of the first sub-divisions lateral to a central sub-division counts five points for its owner. A piece resting in one of the second sub-divisions lateral to a central subdivision counts three points for its owner. A piece resting in one of the third sub-divisions lateral

to a central sub-division counts one point for its owner. The player with the higher score wins.

In order to get a piece into the central sub-division, it is usually necessary for a player to shoot two of his pieces into position near the central sub-division, one to each side thereof, so that one piece or the other may be shot into the central sub-division no matter in what position his opponent places his projector.

Going to Bermuda

Two players seat themselves at opposite ends of the game board. The two central gates 20 are removed and a projector A is mounted in each of the two central sockets 23. The power selector of each projector is positioned at the fifth line on the power selector scale 42.

The target object comprising two parallelepipeds joined by a flat, flexible connecting band, as shown in Fig. 37, will be hereinafter referred to as the gangplank. The gangplank is placed at the center of the playing surface, 20 each parallelepiped resting on one of its rectangular faces not adjacent to said connecton, so that the band is raised above the playing surface of the game board and is substantially parallel to that surface, the gangplank being so positioned that its longitudinal axis lies parallel to the 25 lateral bounding rails 2 and its flexible connecting band is directly above the center of circle T inscribed in the center of the playing surface. A model boat, as shown in Fig. 29, is now placed on its bottom surface on the game board, the longitudinal axis of the boat lying directly 30 over the transverse central line S of the playing surface, and the hump amidships being equidistant from the lateral bounding rails 2. The arrangement of the target objects for the playing of this game is shown in Fig. 50.

Each player is allotted twenty spherical projectiles, the 35 projectiles of each player having a distinctive color to enable the projectiles of one player to be distinguished from the projectiles of the other player. In this game, a player's projectiles will be referred to as his people. The object of each player is to get a couple of his people 40 in the groove atop the boat, one person fore and one person aft of the hump amidships. By chance means, one player is chosen to shoot first. Players then alternate shots. A player attempts to get a person into the boat by projecting it slowly up onto the gangplank. If the 45 projectile is projected in the right direction and at the right speed, it will roll off the gangplank and come to rest in the boat. After each shot, the gangplank and the boat are returned to their starting positions if they have been moved significantly. The game terminates when 50 one player gets a couple of his people in the boat, one person fore and one person aft of the hump amidships. If one person of each player lodges in the boat, both persons are removed and play is resumed. If two persons lodge in the boat fore, or two aft of the hump amidships, the second to arrive is removed. If a player knocks 55 the person of an opponent out of the boat, said person is replaced.

In the playing of certain games, it is intended that the projectors A be used to deflect moving projectiles within 60 the area of the arc determined by the pivotal movement of the projectors. In Figs. 1 and 4, the arc of movement is indicated by the reference character Z, and any projectile or other playing piece which comes within this 65 arc can be deflected by either player by swinging the projector on its pivotal mounting. The same problem is involved when the corner pieces 12 are removed and projectors are mounted at 23^a. Obviously a projector mounted at 23^a would have an arc of movement as indicated, not only to sweep the field while in use as a projector, but as a manual guard. The different games 70 may have different rules for using the projectors as suggested, it being sufficient that the projectors A be of such a length as to cover a desired arc on the panel 1 75 in front of the projector mounting.

What I claim is:

1. A game apparatus comprising a gameboard having a substantially flat and level playing surface, there being along the edge of said playing surface a plurality of pockets or wells whose bottoms lie below the level of said playing surface, said gameboard being bounded by guard rails extending above the level of the playing surface, said guard rails having upwardly opening recesses at spaced points, the bottoms of the recesses being level with the playing surface, the bottom surface being provided with means for mounting projectors thereon, elongated projectors pivotally mounted on said mounting means, said projectors extending inwardly beyond the pockets, targets movably positioned upon the surface of the gameboard, the projectors being pivotally movable to project a projectile against a target or against another projectile which has been projected by an oppositely positioned projector to prevent said projectile from entering a pocket.

2. A game apparatus comprising a gameboard having a substantially flat and level playing surface, there being along the edge of said playing surface a plurality of pockets or wells whose bottoms lie below the level of said playing surface, said gameboard being bounded by guard rails extending above the level of the playing surface, said guard rails having upwardly opening recesses at spaced points, the bottoms of the recesses being level with the playing surface, the bottom surface being provided with means for mounting projectors thereon, elongated projectors pivotally mounted on said mounting means, said projectors extending inwardly beyond the pockets, at least one projector being mounted along the outer edge of one of the pockets, the pocket lying between the projector mounting means and the playing surface, the edge of the playing surface being sufficiently close to the

mounting that the barrel of a projector may be pivoted to overlie the various surfaces bordering said pocket, so that a projectile or target rolling or sliding upon the playing surface toward a certain portion of said pocket may be prevented from entering said pocket either by pivoting the projector to bring the barrel of the projector into the path of said moving projectile or target object or by projecting a projectile from said projector at said moving projectile or target.
